UNITED STATES PATENT OFFICE

ERNEST DAVIS, OF SYRACUSE, NEW YORK, ASSIGNOR TO THE PROSPERITY COMPANY INC., OF SYRACUSE, NEW YORK, A CORPORATION OF NEW YORK

WASHING APPARATUS

Application filed April 12, 1927, Serial No. 183,196. Renewed March 16, 1931.

This invention relates to washing apparatus and has for its object, an apparatus comprising a series of vats movable successively into washing position and in which 5 each vat or tub has a part of a washing machine mechanism associated therewith which is brought into position to be coupled to a main washing machine mechanism when the vat comes into a certain position.

10 The invention consists in means by which the portion of the washing machine mechanism on the vats and the main portion of the washing machine mechanism carried independently of the vats are readily coupled and uncoupled, and in the novel features and 15 in the combinations and constructions hereinafter set forth and claimed.

In describing this invention, reference is had to the accompanying drawings in which 20 like characters designate corresponding parts in all the views.

Figure 1 is a fragmentary side elevation of a washing apparatus embodying my invention.

25 Figure 2 is an enlarged fragmentary sectional view on line 2—2, Figure 1.

Figure 3 is an enlarged fragmentary side elevation of one of the vats and the contiguous parts of the carrier and washing mechanism.

30 Figure 4 is an enlarged fragmentary sectional view through one of the vats and the main washing machine mechanism.

Figure 5 is a fragmentary detail view of the vat and washing machine mechanism associated therewith.

35 Figure 6 is a fragmentary elevation of parts seen in Figure 5 showing the universal joint between the carrier for the main washing machine mechanism and the body therefor.

This washing machine apparatus comprises generally, a series of vats each having a portion or section of washing machine means or mechanism associated therewith, a 45 complementary section or portion of the washing machine mechanism carried independently of the vats and means for moving the series of vats to bring the sections of the washing machine mechanism thereof successively 50 in juxtaposition to the complementary section

of the washing machine mechanism and means for moving the portion of the washing machine mechanism toward and from the vat in juxtaposition thereto to couple and uncouple the complementary section of the 55 main washing machine mechanism and the portion on the vat.

1 designates the series of vats which move along suitable tracks 2 which include upper and lower horizontal runs, each vat having 60 rollers or trucks 3 moving along the tracks and the tracks 2 being in the form of channels, the open sides of which open inwardly, that is, the channels of the tracks on each side of the vats face toward each other and 65 the rollers 3 extend into such channels. The vats are movable along the tracks by a carrier belt or cable 4 which moves over wheels or pulleys 5 at opposite ends of the track, each vat 1 having a bracket 6 depending centrally 70 from its bottom through which bracket the cable 4 extends. The bracket is secured to the cable by suitable means as a set screw 7. The pulleys 5 are provided with suitable cutouts 8 for receiving the brackets 6 as the vats 75 are moving around the end portions of the track. One or the other of the pulleys 5 is connected to a suitable source of power.

Each vat consists of inner and outer receptacles 9 and 10 respectively which are 80 spaced apart to form a chamber 11 between them, and the outer receptacle 10 is formed with a depending neck or outlet conduit 12 located at one side of the center thereof in order to pass by the pulleys 5 during the 85 movement of the series of vats 1 by the cable 4.

The washing machine mechanism associated within each vat 1 may be of any suitable form, size and construction, that here 90 shown being of the type shown in the Cowles Patents, Nos. 1,522,230, January 6, 1925, or 1,545,081, July 7, 1925.

The portion or section of the washing machine mechanism associated with each vat 95 consists generally of one or more jet nozzles 13 discharging into the inner receptacle 9 and suction outlets 14 around the inlet nozzles 13. Each vat is here shown as provided with two nozzles 13 which are connected by pipes 15, 100

located in the chamber 11, to a common intake 17 located within the outlet conduit 12 and concentric therewith. This intake 17 includes a sliding or telescoping coupling pipe 18 projecting beyond the lower end thereof and extending through a packing gland 19 in the lower end of the intake 17. The sliding movement of the coupling 18 is against the action of a spring 20. The packing gland 10 includes a spring 21.

The section or portion of the washing machine mechanism includes a body 22 movable toward and from the conduits 12 and 18 of the vat in juxtaposition thereto in order to make 15 a coupling therewith and to uncouple therefrom. The body 22 has an intake 23 arranged concentric with an outlet 24, the inlet 23 being movable into and out of connection with the intake coupling 18 and the 20 outlet 24 into and out of connection with the outlet conduit 12. The body is formed with an outwardly extending flange 25 complementary to a flange 26 on the conduit 12 and these two flanges are provided with coacting 25 packing rings 27 and 28 on their abutting faces. Also, the intake 23 and the intake coupling 18 are formed with coacting packing rings 29 and 30 on their abutting faces. The body 22 is here shown as carried 30 by a piston 31 movable in a carrier or cylinder 32 which is connected to a suitable source of power as compressed air, through a pipe 33. The cylinder 32 is here shown as formed with trunnions 34 which are pivoted in a 35 yoke 35 which in turn is pivoted at 36 to a base 37. The pivot 36 is arranged at a right angle to the trunnions 34 so that the cylinder 32 and piston 31 have a universal or equalizing action as the flange 25 engages the 40 flange 26. The rocking movement of the yoke 35 is limited by suitable stops 38.

The intake 23 is connected by a pipe 39 to the outlet 40 of a circulating pump 41; the inlet of the pump 41 is connected by a pipe 45 to the outlet 24 of the body 22. The pump intake is also connected, by a suitable conduit 43, to a suitable prime source of supply of fluid, and the pipe 39 is also connected to branch pipes 44 by means of which 50 the fluid can be pumped by the pump 41 to a tank or to some other locality besides the vat 1 in line with the body 22, the branch pipe being controlled by a valve 45. The conduit 43 may be provided with any well known shut-off valve.

There are a plurality of these main washing machine sections, located on a platform 46 arranged below the upper run of vats 1 and the valve 45 may be operated to cause 60 the pump 41 of one mechanism to be connected to the body 22 of one of the other mechanisms. By means of the valve 45, the pump 41 of one section on the platform 46 may be connected to pump fluid into the vat coupled to another section on the platform 46.

It will be understood that in washing clothes in commercial laundries, the clothes are subjected to different fluids as soaking water, suds washing fluid, rinsing fluids, bleaching fluids etc. By means of the branch 70 pipes 44 and the valve 45, the system is made flexible so that a vat after it moves out of registration with one washing machine mechanism may, if desired, be subjected to the same washing operation at the next station. Suitable receivers for the clothes are located 75 below the lower run of vats, these receivers being usually extractors 47.

In operation, the clothes after being sorted, classified and tagged or otherwise identified are taken by the operator from a table 80 48 and placed in the vats 1 and the mechanism for actuating the cable actuated to feed the belt one step. Then the valve 33^a in each feed line 33 is actuated to cause the 85 pistons 31 to be actuated to carry the bodies 22 into connection with the conduits 12 and 18 of the vats in line therewith, the conduits 18 yielding as the packings 27, 28, 29 and 30 come into engagement. The valve 45 is 90 then operated to permit the pump 41 to force the cleansing fluid through the pipe 39, intake 23, coupling pipe 18, intake 17, pipes 15, and jets 13, into the inner receptacle 9 of the vat 1. The suction action of the pump 95 draws the water out through the outlets 14, chamber 11, conduit 12, outlet 24, and pipe 42. This circulation of the water washes the clothes, or rinses them, or performs any other operation.

After this operation has continued for the proper length of time, the valves are operated to cut off the supply of water to the vat and to drain the water therefrom. The valves 33^a are then operated to permit the air to exhaust from the cylinder 32 and hence, to uncouple the coupling bodies 22, of the main washing machine mechanisms, from the vats. The carrier is then caused to be actuated one step after which the operation is 105 repeated. The actuation of the carrier one or more steps brings the vats into registration with different main washing machine mechanisms and also brings the vats 1 which have passed the main washing machine mechanism to the lower run of the belt where the clothes are discharged into the extractors 47. The vats are provided with suitable means as dumping covers for discharging 110 into the extractors 47. This dumping feature forms no part of this invention, but the invention relates primarily to the coupling and uncoupling of the washing machine mechanism of each vat with a main washing machine mechanism.

What I claim is:

1. A washing apparatus comprising a series of vats, each having an inlet and outlet for a washing fluid, means for moving the vats horizontally, mechanism comprising 120

a body having an inlet and an outlet for a fluid and means for forcing the fluid through the inlet and withdrawing the fluid from the outlet, means for lifting and lowering the body to carry the inlet and outlet into and out of connection with the inlet and outlet of the vat in juxtaposition thereto.

2. A washing apparatus comprising a series of vats, each having an inlet and outlet for a washing fluid, means for moving the vats horizontally, mechanism comprising a body having an inlet and an outlet for the fluid and means for forcing the fluid through the inlet and withdrawing the fluid from the outlet, means for lifting and lowering the body to carry the inlet and outlet into and out of connection with the inlet and outlet of the vat in juxtaposition thereto, the vat and the body having concentric passages and abutting end faces provided with packings around the passages arranged to come into engagement, a carrier for the body and a universal mounting for the body on the carrier.

3. A washing apparatus comprising a series of vats, each comprising an inner and outer container, the outer container having an outlet, an inlet located within the outlet and a pipe leading from the inlet to the inner receptacle, an outlet from the inner to the outer container and means for circulating a fluid through the vat comprising a body having an inlet and outlet passage complementary to those of the vat, the body being movable into and out of coupling engagement with the inlet and outlet of the vat and pump means for forcing a fluid through the inlet and outlet passages of the body.

4. A washing apparatus comprising a series of vats, each comprising an inner and outer container, the outer container having an outlet, an inlet located within the outlet and a pipe leading from the inlet to the inner receptacle, an outlet from the inner to the outer container and means for circulating a fluid through the vat comprising a body having inlet and outlet passages complementary to those of the vat, the body being movable into and out of coupling engagement with the inlet and outlet of the vat, said inlets and outlets of the vat and body having abutting end faces and the parts provided with one of said abutting faces being yielding and a pump for circulating the fluid through the inlets of the body and drawing it from the vat through the outlet passages of the vat and the body.

5. A washing apparatus comprising a series of vats, each comprising an inner and outer container, the outer container having an outlet, an inlet located within the outlet and a pipe leading from the inlet to the inner receptacle, an outlet from the inner to the outer container and means for circulating a fluid through the vat comprising a body hav-

ing inlet and outlet passages complementary to those of the vat, the body being movable into and out of coupling engagement with the inlet and outlet of the vat, said inlets and outlets of the vat and body having abutting end faces and the parts provided with one of said abutting faces being yielding, a pump having a discharge pipe connected to the inlet of the body and an intake pipe connected to the outlet of the body, a base and a carrier for the body connected to the base by a universal joint.

6. A washing apparatus including a series of vats, each of said vats having fluid means for washing articles in the vat, mechanism for supplying fluid to the vats, said mechanism comprising a movable element having a part complementary with a part of each of the vats and means for moving said element into and out of engagement with the vat and a pump for circulating the fluid through the element and the vat when the same are connected.

7. A washing apparatus including an endless carrier having upper and lower runs, a series of washing vats mounted upon the carrier, means associated with each of said vats for circulating a fluid therethrough, a mechanism arranged below the upper run of the carrier, means for moving the carrier to bring the vats successively into registration with the mechanism, said mechanism including an element having a surface complementary with the bottom of the vats and being movable toward and from the vats to bring the complementary surface into engagement, and a circulating device for circulating the fluid through the movable element and the circulating means associated with the vat when the complementary surface of said element and a vat are in engagement.

8. A washing apparatus including a series of movable vats, a circulating mechanism independent of said vats and including a movable element having a member complementary with a part of each vat, the vats being movable successively into registration with the circulating mechanism, means for moving the movable element of the mechanism into and out of engagement with a vat when the vat and the mechanism are in registration, and a circulating device associated with the circulating mechanism for circulating a fluid through the movable element and the vat when so engaged.

9. A washing apparatus including in combination a washing vat; means for moving the vat horizontally; a body having inlet and outlet conduits therein; complementary inlet and outlet conduits connected with the washing vat; mechanism for moving one of said inlet conduits and one of said outlet conduits into and out of connection with the other inlet and outlet conduits when the vat is in proper position with respect to said body;

and means for washing the clothes in the vat while the vat is in said proper position.

In testimony whereof, I have hereunto signed my name, at Syracuse, in the county of 5 Onondaga, and in the State of New York, this 28th day of March, 1927.

ERNEST DAVIS.
